FURNACE

Paul C. Lottes, Wilkinsburg, Pa., assignor to Westinghouse Electric & Manufacturing Company, East Pittsburgh, Pa., a corporation of Pennsylvania

Application June 16, 1938, Serial No. 214,031

11 Claims. (Cl. 263—10)

My invention relates generally to electric furnaces of the type having a heating chamber in which a charge is treated while it is enveloped by protective gaseous atmosphere within the heating chamber.

In processes for the heat treatment of metals, and by the term metals I intend to include alloys, it has been found necessary to envelop the metal by a protective gaseous atmosphere in order to prevent deleterious effects upon the metal by reaction thereof with active gaseous components that would otherwise contact the metal. The composition of such a protective atmosphere will depend largely on the kind of metal being heated and the treatment applied to it, as is well known in the art.

In many of the processes, even relatively minute amounts of air contain agents which react with the metal to the detriment of the final product in that the last may be tarnished, or scaled, or have some other objectionable feature. The protective atmosphere can be successively treated to contain only the constituents desired. But during the insertion of a charge into, or the removal thereof from, the furnace, the opening of the door may permit air to enter into the heating chamber, and this must be guarded against. By my invention, I interpose an additional safeguard against the entry of air into the heating chamber of the furnace.

My invention is particularly applicable to electrical furnaces having an entrance chamber, which may also be utilized as a preheating chamber, for the charge. It is customary in such furnaces to purge this auxiliary chamber of air before transferring the charge to the main heating chamber. The purge is accomplished by subjecting the auxiliary chamber to a flow of the protective atmosphere until the atmospheric gases have been driven out. An auxiliary chamber of this sort necessarily has two doors, one through which the charge is inserted into the furnace and the other usually a firedoor between the entrance chamber and the main heating chamber. I have found in practice that it is not entirely common for an operator to open one of the doors without assuring himself that the other door was closed. Such operation permitted unwanted air to get into the main heating chamber, and my invention broadly is for the purpose of preventing the opening of one door while the other is open, or stated in other words, for permitting one door to be open only while the other is closed. In this way, I provide at least an added factor of safety in the operation of a furnace

such as has been just described, although it should be distinctly understood that my invention has many other applications.

It is, accordingly, an object of my invention to provide two doors of a furnace with positive interlock so that one can be opened only while the other is closed.

It is a further object of my invention to provide in a furnace having a main heating chamber, a mechanism in the nature of interlocked doors to insure that the heating chamber is always fully inclosed.

It is still another object of my invention to provide operating mechanisms for two doors which can be independently operated from a single convenient location.

It is a further purpose of my invention to provide an interlock for two operating mechanisms as aforesaid which can be selectively operated in an easy manner to select which of the mechanisms shall be free to open its associated door.

An additional purpose of my invention is to provide an indicator means attached to the operating means that will indicate the proper position of the operating means for the closed position of the doors.

It is still another object of my invention to provide adjusting structure for the interlock whereby it will always be operable regardless of changing dimensions of the door operating means with time.

These and other objects of my invention will be apparent from the following description thereof, taken in conjunction with the drawings, in which

Figure 1 is a view representative, in horizontal section and plan, of a furnace to which my invention may be applied.

Fig. 2 is a front view of the door operating mechanisms and interlock.

Fig. 3 is a sectional view taken along the line III—III of Fig. 2 with both doors shown for the purpose of better illustrating my invention. This figure shows the interlock in one position, whereby one door is locked against movement.

Fig. 4 is a sectional view showing the interlock in a second position whereby the second door is locked against movement.

Fig. 5 is a side view of a modified interlocking mechanism.

Fig. 6 is a sectional view taken along the lines VI—VI of Fig. 5.

The furnace 1 shown in Fig. 1 is representative of the furnace to which my invention can be applied, but it is to be distinctly understood that

my door operating means and interlock is not limited to this particular type of furnace. The furnace 1 has a heating chamber 3 within which are heating units 4 which in this instance are 5 energized by electrical power. At one side of the furnace of the heating chamber is an auxiliary chamber 5 and on the other side is a second auxiliary chamber 7. The auxiliary chambers are separated from a main heating chamber 3 10 by appropriate intermediate fire walls having apertures closed by doors 9 and 11 for the chambers 5 and 7, respectively.

The auxiliary chamber 5 in this particular instance is shown as a charge entrance chamber, 15 that is, it is a chamber in which the charge is placed preparatory to its heat treatment. The chamber 7, on the other hand, is the charge exit chamber. If desired the chamber 5 may also be employed as a preheating chamber while the exit 20 chamber 7 may be employed as a cooling chamber.

The chamber 5 has an opening 13 through which the charge is inserted and this opening is closed by door 15. The chamber 7 is similar in 25 this respect to the chamber 5 and has an opening 17 controlled by a door 19. A push rod 21 sliding in packed journal 23 serves to push the charge from the entrance chamber to the heating chamber 3, while a pull rod 25 sliding in packed 30 journal 27 serves to pull the charge from the heating chamber to the exit chamber 7. In order to insure fairly tight gas seals between the doors and the door jambs (not shown) any of the common expedients may be used, as for example, the 35 doors 9 and 11 are shown as inclined with the walls with which they cooperate similarly inclined.

In operation, each of the chambers may have 40 pipes (not shown) by which a protective atmosphere is led to each chamber and is conducted away therefrom. When it is desired to start the furnace, the doors 9 and 11 are placed in closed position and preferably also the door 19. With the chambers 3 and 7 thus enclosed, the former 45 or both are purged of air by admitting the protective gas atmosphere under pressure for a definite time period. The charge may be placed in the chamber 5, whereupon the door 15 is then closed and this chamber also purged of air.

50 When the air has been eliminated from the chamber 5 to the desired degree, heat may be applied and the door 9 opened when the desired temperature in chamber 3 is reached. A push rod 21 then serves to push the charge into the heating chamber 3, after which the door 9 is then closed. While the charge is being heat treated, a second charge may be inserted into the furnace chamber 5 which is then again purged preparatory to the opening of door 9 to admit the second 55 charge to the heat treating chamber. A sufficient number of charges are placed into the heat treating chamber 3 in accordance with its dimensions.

When it is desired to withdraw the charge after 60 its heat treatment, the reverse procedure is followed, that is, the chamber 7 is purged of air, the door 11 is opened and the pull rod 25 pulls the charge into the chamber 7. After this, the door 11 is closed and the door 19 opened so that the charge may be taken out by opening 17. 65 Obviously, the furnace may have a single or auxiliary chamber which serves as both an entrance or a discharge means, in which case the rod, such as 21, would be of the push-pull type, that is, capable of either pushing the charge or with- 70 drawing it from the heating chamber 3. Or the 75

furnace may have conveyors instead of relying on rods 21 and 25, all as is well known to the art.

The operating mechanisms and their interlock 5 for the doors 9 and 15 are the same as that for the doors 11 and 19 except that the parts are reversed to accommodate the different arrangements of the doors. For the purposes of this description, therefore, one only of the operating mechanisms need be described.

For opening and closing the door 9, a handle 10 29 is provided on a disk 31 rigidly secured by a key or otherwise to a shaft 33. The shaft 33 extends into the furnace and rotates in bearings 35 sealed gas-tight to the furnace walls. Upon the shaft 33 are mounted sprocket wheels 37 over 15 which sprocket chains 39 ride. The chains have one of their ends attached to the door 9 so as to raise and lower it. The turning of the handle 29 turns the shaft 33 to cause the door 9 to be raised or lowered, depending upon the direction 20 of rotation of the handle.

The door 15 is raised or lowered by rotation 25 of the handle 41 which turns the disk 43. The disk 43 is secured to the shaft 45 which is loosely journalled about the shaft 33 so as to be capable of independent rotation with respect thereto. Secured to one end of the shaft 45 in a manner to rotate therewith is a beveled gear 47 meshing with a second beveled gear 49 to which is secured 30 a shaft 51. The shaft 51 is supported at one end by a bearing within a support 53 secured to the furnace wall or any other stationary structure while the other end of the shaft 51 may be additionally supported by a bearing in a support (not shown) also secured to the furnace wall or other 35 stationary structure. A retainer guide 55 which additionally serves to maintain the shafts in proper cooperative relation is U-shaped in form, as shown, and has three apertures through which the shafts 33, 45 and 51, respectively, extend. 40 These apertures being only positioning and guiding means in this construction do not require an exceptionally snug fit.

Upon the shaft 51 are mounted two sprocket 45 wheels 51 over which pass sprocket chains 59 having one of their ends secured to the door 15. To raise and lower the door 15, handle 41 may be rotated. Rotation of the handle 41 turns the disk 43 which, in turn, revolves the shaft 45 and bevel gear 47 about the shaft 33. Rotation of the bevel gear 47 causes rotation of the bevel gear 49 meshing therewith, and this, in turn, rotates the shaft 51 whereupon the door 15 is raised or lowered through operation of the sprocket mechanism.

In order to insure that one of the doors 9 or 55 15 will be closed at all times, I provide an interlock comprising a stationary support 60 having a rod 61 secured thereto. Sliding on this rod is a hollow handle 63 moving an elongated plate 65 60 unitary with the handle and interposed between the two disks. The plate 65 at the end opposite the handle 63 is forked as shown at 67 to straddle the shaft 33, and is thereby maintained in position. Disks 43 and 31 are provided with apertures 69 and 71, respectively into which a lug 73, 65 secured to the plate 65, may enter. The lug 73 extends from both sides of the plate 65 and is of a length somewhat greater than the space 75 between the disks 31 and 43. However, a protruding end of the lug 73 plus the thickness of the plate 65 is less than this space 75.

In order to lock the doors, the apertures 69 and 71 are so spaced as to be aligned only when the doors 9 and 15 are in their closed position. If 76

now it is desired to open one of the doors, the handle 63 is moved so that the lug 73 enters the aperture of the disk associated with the other door. In Fig. 3 is shown the position of the mechanism 5 with the door 15 closed. It may be observed that the lug 73 is in the aperture 69 of the disk 43 and thereby prevents rotation of this disk inasmuch as any attempt to move the handle 41 will tend to rotate the plate 65. However, because of the 10 lug 73 and the rod 61, this plate cannot be rotated so that the door 15 is maintained closed, but inasmuch as the other end of the lug 73 is now clear of the disk 31, the latter can be rotated to control the door 9. The fork 67 provides an 15 additional means to prevent rotation of plate 65, and this fork therefore permits greater clearance between lugs 73 and its associated apertures.

Fig. 4 shows the position of the interlock when it is desired to maintain the door 9 closed and 20 permit control of the door 15 in which case the lug 73 is moved by means of handle 63 so that it enters aperture 71 and is free of the disk 43.

It may thus be seen that by my interlocked doors, an operator cannot open both doors at one 25 time and furthermore it may be observed that since one of the doors 9 and 15 is always closed and one of the doors 11 and 19 is also always closed, the heating chamber 3 is at all times fully inclosed.

30 The mechanism just described for the interlocking of the doors is applicable only where the opening or closing of the doors can be accomplished by less than a complete revolution for the reason that the handle 41 cannot be rotated 35 through a complete circle because of the interpositioned plate 65, and the handle 29 can be deliberately made with a portion 76 (Fig. 1) protruding in the rear of disk 31 so that the plate 65 will interfere with its complete rotation in case 40 the door jamb does not limit the travel of the door to the necessary extents. However, to permit a greater mechanical advantage in opening and closing the doors, I may employ the structures shown in Figs. 5 and 6.

45 In this structure, the shafts 33, 45 and the mechanism connected thereto towards the doors is identical with the structure previously described. However, disks 31' and 43', corresponding to the disks 31 and 43, need not be provided 50 with apertures. Upon the shaft 45 is provided an additional gear 71 which rotates therewith, and upon the shaft 33 is provided an additional gear 79 which rotates with the shaft 33. A fixed support 81 has a base plate 83 to which are attached two extending supporting members 85 and 87, and in these supporting members is journaled a stationary shaft 89.

55 Loosely mounted for free rotation on the shaft 89 are a disc in the form of the gear 91 meshing 60 with gear 77 and a second disk in the form of the gear 93 meshing with gear 79. Apertures are provided in the gears 91 and 93 into which may extend the lug 73' in a manner similar to that described for the previous modification. The 65 apertures are aligned only when the doors 9 and 15 are in closed position, but because of the reduction between the respective pairs of gears 71 and 91 and 79 and 93, the gears 91 and 93 do not make a complete revolution for movement of the 70 doors through their extreme positions. In other words, while the shaft 33 or the shaft 45 may be rotated through any desired number of revolutions to control the doors, nevertheless gears 91 and 93 are limited to movement in an arc of less than 360 degrees. If the number of revolutions 75

required to move one of the doors between its extreme positions is greater than the number of revolutions required to move the other door between its extreme positions, this may be additionally taken care of by changing the ratio 5 between a pair of gears 77 and 91 or 79 and 93, as the case may be.

The lug 73' is secured in a plate 95 so as to be moved when the plate 95 is moved. A rod 97 is attached to the plate 95 and may be pushed 10 in either direction to lock whichever gear, 91 or 93, it may be desired to lock. The rod 97 rests upon the bottom of curved surfaces 99 of plates 101 and 103 secured to the base plate 83 below the gears 91 and 93 respectively. The members 101 15 and 103 further serve as indicating means in conjunction with index pointer fingers 105 and 107 secured to the gears 91 and 93, respectively. The plate 101 has an index arrow 109 which, when aligned with the finger 105 shows the position of the gear 91 with the door 15 closed, and a similar arrow on the member 103 cooperates with the index finger 107 to indicate the proper position of the gear 93 when the door 9 is closed.

20 In order that these indicators shall be accurate and to compensate for discrepancies in the door operating mechanism which may occur during assembly or in the course of time due, for example, to elongation of the sprocket chains, I provide an adjusting means for the gears 91 25 and 93. This means comprises two washers 111 and 113 secured to the shaft 89, and compression springs 115 and 117 normally urging the gears 91 and 93 into position wherein they mesh 30 with their respective gears 77 and 79. However, either of the gears 91 and 93 may be slid along the shaft 89 against the pressure of the springs 115 and 117 until they are out of mesh with the gears on the shafts 33 and 45. When the doors are in closed position, the gears 91 and 93 with their index fingers aligned on the indicator arrows may be released to engage the gears 77 and 79 so that the indicators automatically 35 show the correct position of these gears with the doors closed. As described in the first modification, the lug 73' is of a length somewhat greater than the distance between the gears 91 and 93, and for adjustment purposes it is preferable to so position the lug 73' that the ends thereof are partially within the apertures in 40 both the gears so that both doors can be locked.

45 While I have described my invention in the embodiments which I believe to be the best mode of application thereof, it is obvious that many changes may be made within the spirit and scope 50 of my invention. It is desired, therefore, that the appended claims be given the broadest construction and limited only by the prior art.

55 I claim as my invention:

1. In a device having a pair of doors and operating means therefor comprising a pair of substantially parallel discs, one for each door, means for independently rotating each disc through less than 360° to open and close said doors, and an interlock permitting operation of 60 either one of said doors only while the other is in a predetermined position.

2. In combination, a rotatable shaft, a rotatable disc means secured to said shaft, a handle for rotating said disc means, a second shaft, 70 a second rotatable disc means loosely mounted on said first shaft and connected to said second shaft for rotating the latter, a handle for rotating said second disc means, said discs being spaced apart and substantially parallel, and in- 75

- terlocking means in such space for locking one of said disc means at all times while the other is being rotated.
3. The structure defined in claim 2 wherein said last means comprises apertures in each of said discs which are aligned at a predetermined position of said discs, a pin of a length somewhat greater than said space, and means preventing rotation of said pin and for sliding said pin into one or the other of said apertures.
4. In a furnace chamber comprising two doors, an operating means for one of said doors and comprising a shaft and a disc means secured to said shaft for rotating said shaft, an operating means for the other of said doors and comprising a rotatable disc means loosely mounted on said shaft, said disc means being spaced from each other, and each having apertures which are aligned when said doors are closed, a pin between said disc slideable in said apertures and of a length somewhat greater than said space, and means preventing said pin from rotating and for sliding said pin into one or the other of both of said apertures.
5. A furnace comprising a heating chamber and a secondary chamber, a common wall between said chambers comprising a door, a second door for said secondary chamber substantially at right angles to said first door, a shaft having an inner portion in said secondary chamber and an outside protruding portion, means on said inner portion for operating the first said door upon rotation of said shaft, a disc on said protruding portion and a handle for rotating said disc whereby said first door may be opened or closed, a second shaft substantially parallel with said second door, means on said shaft for operating said second door, a hollow shaft loose about said first shaft, gearing means between said hollow shaft and second shaft, a disc on said hollow shaft and a handle for rotating said disc whereby said second door may be opened or closed, said disc having apertures aligned when said doors are closed, a fixed element, a member slideable on said fixed element, and a pin carried by said member adapted at all times to be within one or the other of said apertures.
6. In a furnace chamber comprising two doors, an operating means for one of said doors and comprising a rotatable member, operating means for the other door and comprising a rotatable member, a pair of gears, reducing gearing be-
- tween one of said rotatable members and one of said gears, reducing gearing between the other rotatable member and the other of said gears, said gears being substantially parallel and an interlock between said gears permitting rotation of one of said rotatable members to open the corresponding door only while the other of said rotatable members is in a predetermined position.
7. The structure of claim 6 in which indicators comprising fingers on each of said gears are provided to indicate the closed position of said doors.
8. The structure of claim 6 in which indicators comprising fingers on each of said gears are provided to indicate the closed position of said doors, and means are provided for adjusting said gears relative to said gearing to insure that said interlock is operable for maintaining said doors closed while said indicators so indicate.
9. The structure of claim 6 wherein means are provided for adjusting said gears relative to said gearing to insure operability of said interlock while the doors are in closed position.
10. A furnace comprising two contiguous enclosed chambers separated by a wall including a door, a second door in an outer wall of one of said chambers, and operating means for said doors comprising a pair of substantially revolute members rotatable in substantially parallel planes, one for each door, means for independently rotating each member through less than 720 degrees to open and close said doors, and an interlock between said rotatable members permitting operation of one of said members only while the other is in a predetermined position.
11. A furnace comprising two contiguous enclosed chambers separated by a wall including a door, a second door in an outer wall of one of said chambers, and operating means for said doors comprising a pair of substantially revolute members rotatable in substantially parallel planes, one for each door, means for independently rotating each member through less than 720 degrees to open and close said doors, and an interlock between said rotatable members permitting operation of one of said members only while the other is in a predetermined position, said interlock comprising a pin of a length somewhat greater than the distance between said members, each of said members having a single aperture therein into which said pin is adapted to slide.

PAUL C. LOTTES.
